Patented Sept. 20, 1966

205,780

HARVESTING MACHINE

Cornelis van der Lely, Zug, Switzerland, assignor to Texas Industries Inc., Willemstad, Curaçao, Netherlands Antilles, a limited-liability company of the Netherlands Antilles

Filed May 19, 1965, Ser. No. 85,408

Claims priority, application Great Britain Nov. 26, 1964

Term of patent 14 years

(Cl. D40--1)

Fig. 1

Fig. 2

FIG. 1

FIG. 2

FIG. 1 is a perspective view of a harvesting machine embodying my new design.

FIG. 2 is a side elevation taken 180° from FIG. 1.

FIG. 3 is a front elevational view with the dotted line portions illustrating the mower blade or reel assembly omitted for convenience of illustration.

FIG. 4 is a rear elevational view thereof.

The dominant features of my design reside in the portions shown in full lines.

I claim:

The ornamental design for a harvesting machine, substantially as shown and described.
